UNITED STATES PATENT OFFICE.

SIMON W. WARDWELL, DECEASED, LATE OF PROVIDENCE, RHODE ISLAND; BY CARL V. J. CHRISTENSEN, OF ATTLEBORO, MASSACHUSETTS, AND EDWIN C. SMITH, ARTHUR A. ARMINGTON, AND WILLARD W. BARDSLEY, OF PROVIDENCE, RHODE ISLAND, EXECUTORS.

DESIGN FOR A FOLDING STAND, TABLE, OR SIMILAR ARTICLE.

Application filed September 27, 1921. Serial No. 503,655. Term of patent 14 years.

To all whom it may concern:

Be it known that SIMON W. WARDWELL, formerly a citizen of the United States, and lately residing at Providence, in the county of Providence and State of Rhode Island, deceased, did during his lifetime invent a certain new, original, and ornamental Design for Folding Stand, Table, or Similar Article; and we, CARL V. J. CHRISTENSEN, EDWIN C. SMITH, ARTHUR A. ARMINGTON, and WILLARD W. BARDSLEY, executors of the estate of SIMON W. WARDWELL, deceased, do hereby declare the following to be a true specification, reference being had to the accompanying drawing, forming a part thereof, in which the single figure of the drawing is a perspective view of a folding stand or table showing the new design.

We claim:—

The ornamental design for a folding stand, table or similar article as shown.

CARL V. J. CHRISTENSEN,
EDWIN C. SMITH,
ARTHUR A. ARMINGTON,
WILLARD W. BARDSLEY,

Executors of the Estate of Simon W. Wardwell, Deceased.
